CONVERSION OF HYDROCARBON OILS

Filed Aug. 25, 1939

UNITED STATES PATENT OFFICE

2,327,973

CONVERSION OF HYDROCARBON OILS

Charles L. Thomas, Chicago, Ill., assignor to
Universal Oil Products Company, Chicago, Ill.,
a corporation of Delaware

Application August 25, 1939, Serial No. 291,890

6 Claims. (Cl. 196—52)

This invention relates to the conversion of crude petroleum into substantial yields of motor fuel products and is a continuation-in-part of my co-pending application Serial No. 166,570, filed September 30, 1937. The process may also be applied to similar hydrocarbon distillates from other sources, such as shale oils, coal tars, etc.

More specifically, the invention concerns a combination of catalytic and non-catalytic cracking with a definite interrelation of steps so that maximum benefits are obtained, not only in respect to yields and antiknock value of the finished gasoline, but also in respect to the life of the catalytic masses employed in the catalytic cracking step.

The limitations of ordinary non-catalytic cracking in the production of high yields of antiknock gasoline are fairly well recognized. The increasingly severe conditions of temperature and pressure employed in increasing the antiknock value of the motor fuel product results, after a certain point, in disproportionately large losses as gas and residue, so that the overall economics of such an operation reaches a more or less definite value.

In order to increase the antiknock value for a given yield of gasoline, various catalytic masses have been used. Such catalytic masses have not been universally applicable to all types of hydrocarbon oils particularly heavier fractions, such as topped crude oil, reduced crude oil, etc. They have been used with considerable success for processing distillate fractions of crude petroleum, particularly such fractions as may be distilled at atmospheric pressure without substantial decomposition, such as gas oils, kerosene, and the like.

During the catalytic cracking of petroleum fractions, carbonaceous deposits develop on the catalytic surfaces, necessitating frequent reactivation by means of oxygen-containing gas. When heavier fractions, such as topped crude oils, are cracked catalytically, the amount of such deposits becomes disproportionately large, and as a result reactivation becomes difficult, and in some cases, is definitely harmful to the catalytic life because of the amount of carbon which must be consumed and the consequent development of inordinately high temperatures during reactivation. For this reason the charging stocks used in catalytic cracking are more or less limited to distillate fractions. The present process, the character of which will be developed in succeeding paragraphs, is a novel contribution to the art of cracking hydrocarbon oils for increased yields

and anti-knock value by the combination of catalytic and non-catalytic cracking operations.

In one specific embodiment the present invention comprises a process for converting crude hydrocarbon oil into substantial yields of high octane number gasoline, which comprises charging said hydrocarbon oil to a primary fractionator, subjecting the heavy unvaporized portion of the oil to cracking treatment in a non-catalytic cracking step comprising a primary tubular heating coil communicating with a reaction chamber operated under conditions adequate to effect substantial conversion to gas and gasoline, passing the reaction products to a vaporization step at reduced pressure, separating a residue unsuitable for further conversion, passing the vaporized products to the primary fractionator, separating therefrom the gas, gasoline, and an intermediate boiling fraction and a relatively heavy fraction, returning said relatively heavy fraction to the non-catalytic cracking step, contacting said intermediate-boiling fraction in vaporous form with a cracking catalyst in a catalytic cracking step under conditions adequate to effect substantial cracking thereof, passing the reaction products from said catalytic cracking step to a secondary fractionation step, recovering the gas, gasoline and insufficiently converted oil, passing a portion of said insufficiently converted oil to a secondary tubular heating coil operated at temperatures and pressures substantially higher than the primary tubular heating coil, said secondary coil communicating with said reaction chamber, and returning a second portion of said insufficiently converted oil to said catalytic cracking step.

The various cooperative features of the present invention may be further understood from a description of a process flow, and for this purpose the accompanying drawing has been provided which shows by the aid of conventional figures a diagrammatic outline of interconnected units in which the process may be conducted. The apparatus has not been drawn to scale nor has any attempt been made to proportionate the various units thereof. Furthermore, heat exchangers, condensers, stabilizers, and various other parts of equipment conventionally used in the operation of cracking units have been omitted in the interests of simplifying the drawing. The invention should not be construed as limited to the exact apparatus or conditions given therein.

Referring to the drawing, the raw oil charge enters the system through line 1, valve 2, pump 3, valve 4, line 5 and enters the lower section of

fractionator 6. If gas or gasoline is present it is removed through line 7 and valve 8 through suitable stabilizers, heat exchangers, condensers, etc., not shown. The high-boiling unvaporized fraction of the crude oil is withdrawn through line 9, valve 10, pump 11 and valve 12 to primary or heavy-oil heating coil 13 which is disposed in furnace 14. The pressure and temperature are increased to a suitable point and the oil is passed through line 15 and valve 16 into reaction chamber 17 where substantial conversion to gas and gasoline occurs. The reaction products are removed through line 18 and valve 19 and passed into flash chamber 20 wherein the pressure is reduced and substantial vaporization of the oil occurs. A residue unsuitable for further conversion is withdrawn through line 21 and valve 22. The vaporized portion passes overhead through line 23 and valve 24 into fractionator 6. The gas and gasoline are removed overhead through line 7 and valve 8. An intermediate-boiling fraction including that present in the raw oil charge as well as that produced during the non-catalytic cracking step is removed through line 25, valve 26, pump 27 and valve 28 to coil 29 which is disposed in furnace 30. The pressure at this point may be atmospheric or only sufficiently superatmospheric to insure the passage of the oil vapors through the various parts of the apparatus. The oil vapors are passed through line 31 and valve 32 to catalytic converter 33 which may comprise any suitable type of catalytic reactor such as reaction chambers containing the catalytic mass or tubes disposed within a heated zone, the catalyst being placed in said tubes. The reaction products pass through line 34 and valve 35 to secondary fractionator 36. The gas and gasoline are removed through line 37 and valve 38 from which they pass to suitable condensers, etc., not shown. From this point a number of alternative flows are possible.

The preferred alternative consists in returning a portion of the insufficiently converted oil to the catalytic cracking step by way of a light-oil coil operating at a temperature and pressure substantially above those employed in heating the heavy fraction of the raw oil charge prior to passage to the reaction chamber. The intermediate fraction may be withdrawn through line 39, valve 40, pump 41, valve 42 to secondary or light-oil heating coil 43 which is disposed in furnace 44 wherein it is heated to a suitable cracking temperature. The hot oil passes through line 45 and valve 46 to reaction chamber 17. Simultaneously a high-boiling fraction of the insufficiently converted oil from the catalytic cracking step may be withdrawn through line 47 and valve 48 to storage.

Another portion may be withdrawn through line 49 and valve 50 by pump 51 and valve 52, line 53 and valve 54 to flash chamber 20. A part or all of the heavy oil is withdrawn through valve 48 and may be passed through line 55 and valve 56 which joins with line 39 and passes thence to the light-oil coil. A further intermediate-boiling fraction somewhat heavier than that withdrawn through line 39 may be removed through line 57, valve 58, pump 59, line 60 and valve 61 which joins with line 25 and pass thence by previously described routes to the catalytic cracking step.

According to another alternative reaction a portion of the intermediate-boiling fraction from line 57 may be passed through line 62 and valve 63 which joins with line 5 and is thence returned to fractionator 6. If desired instead of

being returned to fractionator 6 a portion of this intermediate fraction may be passed through line 64 and valve 65 and returned together with the high-boiling fraction from lines 47 and 49 to either the light-oil coil by means of line 55, valve 56, line 39 and valve 42 or may be passed through line 53 and valve 54 to the flash chamber.

It is possible from the drawing that only one intermediate-boiling fraction need be withdrawn from fractionator 36, said fraction being withdrawn through either line 39 or line 57 and processed as previously described.

The thermal cracking step may be operated at pressures of 100-500 pounds per square inch or higher and temperatures within the range of approximately 850°-1000° F. The catalytic cracking step may be operated at substantially atmospheric or slightly superatmospheric pressures of the order of 50-100 pounds per square inch and temperatures of 800°-1200° F.

Numerous types of cracking catalysts may be used, among which are fuller's earth or other clays, including montmorillonite, bentonite, etc., which have been treated with acids or other chemicals to increase their activity and which may have added metal oxides disposed thereon to serve as promoters of catalytic cracking.

Another type of catalyst which has been particularly useful comprises a composite of a major portion of precipitated silica having added thereto minor portions of precipitated alumina and/or zirconia, said catalytic masses being substantially free of alkali-metal compounds. These catalytic masses are prepared by mixing the precipitated and washed hydrogels or coprecipitating the masses under conditions whereby alkali-metal compounds are substantially eliminated. The masses are then formed into suitable shapes by compression or extrusion methods, dried, and calcined at temperatures in excess of 800° F. prior to their use in the process. The ratio of the added compound to silica may vary over a considerable range and is normally within the limits of approximately 5-30% by weight.

The charging stocks used in this process may comprise distillate fractions of crude petroleum, crude petroleum oils or other fractions such as topped crude oils or similar hydrocarbon oils from other sources.

The following example is given for purposes of illustration and should not be interpreted as limiting the process to the exact conditions given therein.

A 26° A. P. I. gravity Midcontinent topped crude oil was charged to fractionating column 6 and the unvaporized portion was passed through coil 13 and reaction chamber 17 where it was cracked at a temperature of 950° F. and a pressure of 400 pounds per square inch. The reaction products were passed to flash chamber 20 from which residual fuel oil having a furan viscosity of 500 seconds at 122° F. was withdrawn. The vaporized products were passed to fractionator 6 where the gas and gasoline were removed overhead. An intermediate fraction of approximately 35 gravity was removed and passed through coil 29 to catalytic converter 33 which was operated at substantial atmospheric pressure and a temperature of 975° F. The vapors were contacted with a precipitated silica-alumina-zirconia mass. The reaction products were passed to fractionator 36 from which gas and gasoline were removed. The high-boiling fraction of the insufficiently

converted bottoms was removed through lines 47, 48, 55 and 39 to light-oil coil 43 and mixed with a low-boiling intermediate fraction from line 38. The light-oil coil was operated at 500 pounds pressure and 950° F. The heated oil passed then to reaction chamber 17. A higher-boiling intermediate fraction was removed from fractionator 36 through line 57 and returned through lines 60 and 25 to the catalytic cracking step. A total yield of approximately 61% of gasoline including that formed by polymerizing the C₃ and C₄ olefins from both cracking steps was obtained. The catalytically cracked fraction had an octane number of 81 and the thermally cracked portion had an octane number of 72. The blend was 76 octane number 400° F. end-point motor fuel. The yield of cracked gasoline obtainable from this stock by non-catalytic cracking alone was approximately 51%.

I claim as my invention:

1. A process for converting a hydrocarbon oil into substantial yields of relatively high anti-knock gasoline which comprises charging said oil to a primary fractionation step, separating a heavy non-vaporous fraction of the oil, subjecting said fraction to non-catalytic cracking in a primary cracking step by passage through a heating coil and communicating reaction chamber at a temperature and pressure adequate to effect substantial cracking thereof, passing the reaction products into a vaporizing zone at a reduced pressure, separating and recovering therefrom a heavy fraction unsuitable for further conversion, passing the vaporous portion of said reaction products to said primary fractionation step, removing the gas and gasoline, separately removing from said fractionating step, an intermediate-boiling fraction, comprising components of the charging oil not previously subjected to cracking conditions in the process, and contacting the same with a catalyst in a secondary cracking step under conditions adequate to effect substantial cracking thereof, separating gas and gasoline from the products of the secondary cracking step in a secondary fractionation step and recovering the same, returning an intermediate-boiling fraction of insufficiently converted oil separated from the last named products to said secondary cracking step, and supplying a higher-boiling fraction of said insufficiently converted oil to a secondary heating coil communicating with said reaction chamber of said primary cracking step and subjecting the same in said secondary coil to independently controlled cracking conditions of temperature and pressure.

2. A process for converting a hydrocarbon oil into substantial yields of relatively high anti-knock gasoline which comprises charging said oil to a primary fractionation step, separating a heavy non-vaporous fraction of the oil, subjecting said fraction to non-catalytic cracking in a primary cracking step by passage through a heating coil and communicating reaction chamber at a temperature and pressure adequate to effect substantial cracking thereof, passing the reaction products into a vaporizing zone at a reduced pressure, separating and recovering therefrom a heavy fraction unsuitable for further conversion, passing the vaporous portion of said reaction products to said primary fractionation step, removing the gas and gasoline, separately removing from said fractionating step an intermediate-boiling fraction and contacting

the same in vaporous form with a catalyst in a secondary cracking step under conditions adequate to effect substantial cracking thereof, separating resulting gas and gasoline in a secondary fractionation step and recovering the same, separating resulting insufficiently converted oil into a low-boiling fraction, an intermediate-boiling fraction, and a residual fraction returning the intermediate-boiling fraction of said insufficiently converted oil to said secondary cracking step, mixing the low-boiling fraction and the residual fraction of said insufficiently converted oil and passing the mixture to a secondary heating coil communicating with the aforesaid reaction chamber of said primary cracking step and subjecting the same in said secondary coil to independently controlled cracking conditions of temperature and pressure.

20 3. A process for converting a hydrocarbon oil into substantial yields of relatively high anti-knock gasoline which comprises charging said oil to a primary fractionation step, separating a heavy non-vaporous fraction of the oil, subjecting said fraction to non-catalytic cracking in a primary cracking step by passage through a heating coil and communicating reaction chamber at a temperature and pressure adequate to effect substantial cracking thereof, passing the reaction products into a vaporizing zone at a reduced pressure, separating and recovering therefrom a heavy fraction unsuitable for further conversion, passing the vaporous portion of said reaction products to said primary fractionation step, removing the gas and gasoline, separately removing from said fractionating step an intermediate-boiling fraction and contacting the same in vaporous form with a catalyst in a secondary cracking step under conditions adequate to effect substantial cracking thereof, passing the resulting gas and gasoline in a secondary fractionation step and recovering the same, separating resulting insufficiently converted oil into a low-boiling fraction, an intermediate-boiling fraction, and a residual fraction, passing the low-boiling fraction to a secondary heating coil communicating with the aforesaid reaction chamber of the non-catalytic cracking step and subjecting the same in said secondary coil to independently controlled cracking conditions of temperature and pressure, returning the intermediate-boiling fraction of said insufficiently converted oil to said secondary cracking step, and passing the residual fraction to the aforesaid vaporizing zone of said primary cracking step.

4. A process for converting a hydrocarbon oil into substantial yields of relatively high anti-knock gasoline which comprises charging said oil to a primary fractionation step, separating a heavy non-vaporous fraction of the oil, subjecting said fraction to non-catalytic cracking in a primary cracking step by passage through a heating coil and communicating reaction chamber at a temperature and pressure adequate to effect substantial cracking thereof, passing the reaction products into a vaporizing zone at a reduced pressure, separating and recovering therefrom a heavy fraction unsuitable for further conversion, passing the vaporous portion of said reaction products to said primary fractionation step, removing the gas and gasoline, separately removing from said fractionating step an intermediate-boiling fraction and contacting the same in vaporous form with

a catalyst in a secondary cracking step under conditions adequate to effect substantial cracking thereof, separating resulting gas and gasoline in a secondary fractionation step and recovering the same, separating a relatively low-boiling fraction and a higher-boiling fraction of the resulting insufficiently converted oil, passing said relatively low-boiling fraction to a secondary heating coil communicating with said reaction chamber of said primary cracking step and subjecting the same in said secondary coil to independently controlled cracking conditions of temperature and pressure, and returning the higher-boiling fraction of insufficiently converted oil to the secondary cracking step.

5. A process for converting a hydrocarbon oil into substantial yields of relatively high anti-knock gasoline which comprises charging said oil to a primary fractionation step, separating a heavy non-vaporous fraction of the oil, subjecting said fraction to non-catalytic cracking in a primary cracking step by passage through a heating coil and communicating reaction chamber at a temperature and pressure adequate to effect substantial cracking thereof, passing the reaction products into a vaporizing zone at a reduced pressure, separating and recovering therefrom a heavy fraction unsuitable for further conversion, passing the vaporous portion of said reaction products to said primary fractionation step, removing the gas and gasoline, separately removing from said fractionating step an intermediate-boiling fraction, comprising components of the charging oil not previously subjected to cracking conditions in the process, and contacting the same with a catalyst in a secondary cracking step under conditions adequate to effect substantial cracking thereof, separating resulting gas and gasoline in a secondary fractionation step and recovering the same, separating a relatively low-boiling fraction and a higher-boiling fraction of the resulting insufficiently converted oil, and passing the higher-

boiling fraction of the insufficiently converted oil to a secondary heating coil communicating with the reaction chamber of said primary cracking step and subjecting the same in said secondary coil to independently controlled cracking conditions of temperature and pressure.

6. A process for converting a hydrocarbon oil into substantial yields of relatively high anti-knock gasoline which comprises charging said oil to a primary fractionation step, separating a heavy non-vaporous fraction of the oil, subjecting said fraction to non-catalytic cracking in a primary cracking step by passage through a heating coil and communicating reaction chamber at a temperature and pressure adequate to effect substantial cracking thereof, passing the reaction products into a vaporizing zone at a reduced pressure, separating and recovering therefrom a heavy fraction unsuitable for further conversion, passing the vaporous portion of said reaction products to said primary fractionation step, removing the gas and gasoline, separately removing from said fractionating step an intermediate-boiling fraction and contacting the same in vaporous form with a catalyst in a secondary cracking step under conditions adequate to effect substantial cracking thereof, separating resulting gas and gasoline in a secondary fractionation step and recovering the same, separating a relatively low-boiling fraction and a higher-boiling fraction of the resulting insufficiently converted oil, passing the relatively low-boiling fraction of insufficiently converted oil to a secondary heating coil communicating with the reaction chamber of said primary cracking step and subjecting the same in said secondary coil to independently controlled cracking conditions of temperature and pressure, and returning the higher-boiling fraction of said insufficiently converted oil to said secondary cracking step.

CHARLES L. THOMAS.
